DISTANCE SIGHT MEASURING DEVICE

Maxwell O. Thompson, 701 Lokchapee Drive,
Macon, Ga. 31204

Filed July 21, 1970, Ser. No. 24,045

Term of patent 14 years

Int. Cl. D10—08

U.S. Cl. D52—6

FIG. 1 is a front elevational view of a distance sight measuring device showing my new design; and

FIG. 2 is a left-end elevational view of FIG. 1, the right end being substantially identical; and

FIG. 3 is a top plan view of FIG. 1, the bottom plan view being substantially identical; and

FIG. 4 is a rear elevational view.

I claim:

The ornamental design for a distance sight measuring device, as shown and described.
